UNITED STATES PATENT OFFICE

2,287,096

GROUP CONTINUOUS ELECTRIC OUTLET

Herman Friend, New York, N. Y.

Application August 1, 1940, Serial No. 349,040

10 Claims. (Cl. 173—334.1)

This invention relates to outlets for electric current in buildings and other appropriate places, and has for its main object to provide a device wherein a group of electric outlets are arranged, the individual outlets of the group being connected to two continuous main conductors.

Other objects of this invention will be apparent as the specification of the same proceeds, and among others I may mention: to provide a device as characterized hereinbefore, in which all the electro-conductive parts are safely insulated and only distinct separate individual openings or sockets are left for the insertion of the various plugs for the outlets of the electricity; to provide a device as characterized hereinbefore, which will be extremely simple in construction, cheap to manufacture and easy to assemble, to apply or to remove; to provide a device which may be used independently of the parts of the building as a separate independent unit or which may be built into the walls of the building to any length desired, and which may be adapted to be used as a regular molding of the building at the same time possibly also being adapted to carry additional wires, like those of the telephone connection.

In the drawing forming a part of this specification and accompanying the same:

Fig. 1 is a sectional elevation through that form of the device which is adapted to be built into the wall of the building, and

Fig. 2 is a front elevation thereof;

Fig. 3 is a perspective detail showing an improved form of my main conductors;

Fig. 4 is a perspective view of a portable device built according to my invention;

Fig. 5 is a perspective end elevation showing a modification of the housing of my device;

Fig. 6 is a fragmentary plan view of a novel corner connection between my main electric conductors, and

Fig. 7 is a sectional elevational view taken on the line 7—7 of Fig. 6.

Referring now to the drawing more in detail by characters of reference, the numeral 10 represents a central insulator bar used in my device, one form of the cross section thereof being indicated in Fig. 1, but, of course, the same may take any other appropriate cross section, either to have a more decorative front profile for the same instead of the outwardly curved one shown in the drawing, or to have it entirely flat and in the plane of the wall into which my device is intended to be built.

An upper main electric conductor 12 is placed over the central insulator bar 10 in the position indicated in Fig. 1, said upper main conductor having an inner branch 13 placed on top of the central bar 10, and an outer branch 14, the two being connected with a curved portion 15. The conductor 12 is made of highly electro-conductive, but resilient sheet material, like brass, copper, etc.

10. The inner end 16 of the inner branch 13 is bent in an inclined manner, as indicated, and fits into the inclined groove 17 at the upper inner edge or corner of the central bar 11.

An insulating cover, generally indicated by the numeral 19 is placed over the upper main conductor 12 in the manner obvious from Fig. 1, said insulator protecting cover 19 being made of any appropriate insulating sheet material, like Bakelite, hard rubber, or other similar compositions,

20 and in the preferred form shown, it has an upper sheet portion 18, a rear transverse portion 20, a rear base portion 21, (indicated in the lower portion of Fig. 1) the inner end of said base portion being folded into a triangular form, as indicated

25 at 22, adapted to fit into the triangular slot 17 in the upper inner corner of the central insulating rod 10, and over the inclinedly bent portion 16 in the rear of the main conductor 12.

The front portion of the insulating cover 19

30 has a downward branch 23 being brought close to or in contact with the central bar 10, as indicated at 24.

At the lower or opposite side of the central bar 10, a lower main conductor 25 is arranged

35 being identical to the upper conductor 12, but oppositely placed, and, similarly, an insulation cover 26 is also arranged at the other side of the bar 11 for the second main conductor 25, being identical to the upper insulator cover 19, but

40 placed reversely thereto.

A housing or casing 27 is provided for my device having upper and lower main transverse portions 28 and 29, upper and lower front portions 30 and 31 bent over the respective front

45 portions 23 of the insulator covers, but having a space 32 left between their inner edges and the respective portion of the central bar 10. The casing 27 will also have upper and lower rear transverse portions 33 and 34 and upper and lower

50 base portions 35 and 36, and a rear or bottom portion 37.

As will be seen, the stepped inner or bottom portion of the casing will fit snugly over the inner portion of the central bar 11 with the inner ends of the upper and lower conductors and

insulators covers added to it, and will keep said conductors and insulator covers in their places by frictional action, as indicated in Fig. 1.

My device, the construction and parts of which have been explained in connection with the sectional elevation of Fig. 1, may have any desired length, and such a length thereof will be built into the wall 38 of the building, the upper and lower conductors having electro-conductive insulated wires secured thereto, said wires being connected to the next available source of current in the building in any appropriate manner the details of such securing end connections being understood by those versed in this art and not being shown in the drawing.

The front elevation of Fig. 2 shows a certain length of my device built into the wall of the building, the left hand and right hand limits thereof being indicated as at 41 and 42.

At appropriate distances from one another, upper and lower sockets or apertures 43 and 44 may be provided in the marginal portion of the insulator covers 18 and 26, respectively, said apertures 43 and 44 being diagonally opposite to one another and adjoining the central bar 10, as will be understood.

The apertures or openings 43 and 44 serve as the socket for a usual electrical plug, one standard form of which is indicated at 45.

The use and operation of my device will be obvious from the herein description, but I desire to offer the following further remarks relating thereto:

When it is desired to plug in to the electric current connected to the upper and lower main conductors 12 and 25, respectively, a plug 45 will be moved in the direction of arrow 46 and its prongs 47 and 48 will be pushed through the apertures or sockets 43 and 44 and will be pushed between the inner branches 13 of the upper and lower main conductors 12 and 25, and the upper and lower surfaces 10a and 10b of the central insulating bar 10, and, through the resilient action of said main conductors, they will have a close contact therewith along their whole outer surface, and said prongs 47 and 48 will be snugly held in the sockets 43 and 44 and to the rear of them.

In this manner, any desired electrical devices or instruments may be connected to my main conductors 12 and 25, and through them to the house current through the various pairs of sockets 43 and 44.

It is obvious that my device may be built into the wall of any desired room in a building, or apartment, or a shop, warehouse, office, etc., and it may have any desired length therein. If desired, it may run along the whole length of a wall, and it may even run around the corners and be built into two or more walls along their entire length to make the original current fed to their continuous main conductors 12 and 25 available at any desired place in the room in question in a quick and safe manner.

The front of my device may be developed in an ornamental manner, or it may be painted similarly to the rest of the wall so that only the sockets 43 and 44 will be observable.

The central bar 10, the insulator covers, and the outer housing of my device may be made of any desired length, easily put together, and the main conductors 12 and 25 may have unlimited lengths, so that no electric break will be necessary in said conductors no matter how long a

group continuous electric outlet device will be built according to my invention.

Indeed, main conductors according to this invention may be manufactured and shipped in 5 rolls of great lengths and cut to the desired lengths when my device is built and assembled, but, of course, my device also may be assembled and shipped ready from the factory in any desired lengths.

10 In Fig. 3 I indicate a modified form of my main conductors, the one shown in Fig. 3 being the upper conductor 12, but of course, the lower conductor 25 may be manufactured in an entirely similar form. In this modification, the 15 upper or outer branch 14 and the curved connecting portion 15 may have incisions 49 at predetermined distances, such incisions increasing the yielding and elastic character of the device.

It will be obvious that, notwithstanding such 20 incisions, the intact portion of the whole conductor 12 will take care of the safe conducting of the electricity throughout the entire length of the main conductor 12. It is also obvious that, vice-versa, incisions may be made at certain places in the inner branch 13 also, as indicated at 50, or that the incisions 49 may partly go over into the inner branch 13, and the incisions 50 may partly go over into the outer branch 14, as desired.

25 30 In Fig. 4 I indicate a specific portable form of my device, generally indicated by the numeral 51, which as to its construction, operation and use, is entirely similar to the one indicated in Figs. 1 and 2 and described hereinbefore in detail. The only difference being that the same 35 is made of a desired length assembled and shipped ready from the manufacturing place, and it may have two end closure plates 52 of insulating material or insulated from the conductors 12 and 25 therein.

40 The upper and lower main conductors have insulated wires 53 and 54 connected therewith, said insulated wires terminating in a plug 55 by which the device may be plugged into any appropriate outlet or socket at the place of use. 45 In this manner, a group of outlets are provided through my portable device at any place desired, like a shop, kitchen, etc., without any special construction, assembly and building, and said group outlet may be removed at any time desired.

40 Into the outlet sockets thereof any desired instrument or device like tools, lights, machines, electrical devices, irons, etc., may be plugged in.

55 55 In Fig. 5 I illustrate a modification for the housing of my device. The housing of my device in this modification may have an upper ornamental extension 56 by which the same may be formed into an ornamental molding, and in 60 this manner, may be used along the wall of the building or along the corners of the floor. In this modification, I may provide a channel 57 into which insulated wires may be placed so that my novel molding will provide means to carry wires 65 for other purposes, like for the telephone, such wires being placed into the channel 57 through its open end 58, or similarly removed therefrom when desired.

70 It will be obvious that the ornamental molding 56 may take many other forms and the channel 57 may also be of many other formations and arrangements therein.

75 My group continuous outlet device may be secured into the wall by any desired manner; through-going screws 59 being indicated in the

drawing, and such screws may also be used with the movable embodiment 51 of Fig. 4, or it may be secured in its place by any other obvious manner.

In Figs. 6 and 7, I indicate one form of corner connection for my continuous group electric outlets when it is desired to carry them around a corner of a building.

In the fragmentary view of Fig. 6, the end of my device in one of the walls is indicated by the numeral 60, and the end of the other one by the numeral 61, and the ends of the respective upper main conductors by the numerals 12a and 12b. An angular electro-conductive metal piece 62 is provided in the corner for the electrical connection between the devices 12a and 12b, its respective branches 62a and 62b being pushed between the inner and outer branches of the respective conductors 12a and 12b, as generally indicated in Fig. 7. In this manner, without any instrument or securing means, a very reliable strong electrical connection may be provided between the corner piece 62 and the two main conductors 12a and 12b, and the respective front edges of the extension 62a and 62b may be made rounded to fit into the rounded portions 15 connecting the upper and lower branches 13 and 14 of the respective main conductors 12a and 12b.

I also want to remark that to insure that the prong 47 will not by accident make a short circuit contact with the edge of the front 30 of the outer casing, the portion of the insulator 19 separated to make the aperture 43 preferably is bent upwardly, as at 63, to cover the edge of the outer casing at that place.

It is obvious that the respective lower apertures 44 may be treated in a similar manner and covered by a portion of the insulating device, as at 64.

What I claim as new, is:

1. In a continuous group electric outlet, having a central longitudinal insulating bar and an elongated plate-like electric conductor resiliently yieldingly placed against each of the two sides of said central bar, a plate-like elongated insulator cover placed over each of said conductors covering their front, rear, and their broad outer sides, the rear portions of the conductors and of the insulator covers closely fitting against the rear portions of said outer sides of the central insulator bar, and an elongated housing of sheet material for the device, the front part of the side walls thereof being spaced apart from said insulator covers, and the rear portions of them being set closely over the rear portions of the insulator covers, the front of said insulator covers and said housing exposing the front of said insulator bar, and the rear wall of said housing snugly fitting against the back of said central insulator bar whereby said insulator covers and said conductors are held in place at the sides of said insulator bar, means being provided between the sides of said insulator bar and the front of said insulator covers and of said housing, whereby the prongs of an electric plug may be inserted between the respective sides of said insulator bar and the conductors on them, said conductors pressing against said prongs by resilient action.

2. In a continuous group electric conductor, as set forth in claim 1, depressions in the rear of said insulator bar, the rear portions of said conductors and said insulator covers being hooked into said depressions.

3. In a continuous group electric outlet, as set

forth in claim 1, the front edges of said insulator covers being closely set against the respective sides of said central insulator bar, and the edges in the front opening of said housing being at a pre-determined distance therefrom, apertures being provided in said insulator covers adjacent to said insulator bar to permit the insertion of said prongs at pre-determined places, the material of said insulator covers at said apertures being bent outwardly over the adjacent portions of the edges of the front of said housing to protect the material of said housing from contacting said prongs.

4. In a portable continuous group electric outlet, having a central longitudinal insulating bar and an elongated plate-like electric conductor resiliently yieldingly placed against each of the two sides of said central bar, a plate-like elongated insulator cover placed over each of said conductors covering their front, rear, and their broad outer sides, the rear portions of the conductors and of the insulator covers closely fitting against the rear portions of said outer sides of the central insulator bar, and an elongated housing of sheet material for the device, the front part of the side walls thereof being spaced apart from said insulator covers, and the rear portions of them being set closely over the rear portions of the insulator covers, the front of said insulator covers and said housing exposing the front of said insulator bar, and the rear wall of said housing snugly fitting against the back of said central insulator bar whereby said insulator cover and said conductors are held in place at the sides of said insulator bar, means being provided between the sides of said insulator bar and the front of said insulator covers and of said housing, whereby the prongs of an electric plug may be inserted between the respective sides of said insulator bar and the conductors on them, said conductors pressing against said prongs by resilient action, two end walls for said housing and two insulated electric conductors passing through one of said end walls to connect the elongated plate-like conductors in the device to the respective poles of a source of current, and means to secure said central insulator bar to the rear wall of said housing.

5. A continuous group electric outlet, comprising an elongated housing of sheet material, having side walls, a rear wall, and an open front wall, an insulator bar on the rear wall of said housing substantially extending the whole length of the housing, the front of said bar being exposed through the opening in the front wall, two elongated sheet electric conductors resiliently yieldingly placed against the two sides of the insulator bar, an elongated plate-like insulator cover placed over each of said conductors, having a front wall, space being left between the front walls of the housing and the insulator covers, and the respective sides of the insulator bar, whereby prongs of an electric plug may be inserted between the respective sides of the bar and the conductors thereon, the front portion of said conductors being folded doubled in a generally U shaped cross section, with a rounded front or bottom wall for said U, to increase the resilient action of said conductors and to facilitate the insertion of said prongs, said insulator covers providing wider spaces at the doubled portions of said conductors, the rear of the conductors and of the insulator covers, however, being closely set against the rear portion of the insulator bar.

6. A continuous group electric outlet, comprising an elongated housing of sheet material, having side walls, a rear wall, and an open front wall, an insulator bar on the rear wall of said housing substantially extending the whole length of the housing, the front of said bar being exposed through the opening in the front wall, two elongated sheet electric conductors resiliently yieldingly placed against the two sides of the insulator bar, an elongated plate-like insulator cover placed over each of said conductors, having a front wall, space being left between the front walls of the housing and the insulator covers, and the respective sides of the insulator bar, whereby prongs of an electric plug may be inserted between the respective sides of the bar and the conductors thereon, the front portion of said conductors being folded doubled in a generally U shaped cross section, with a rounded front or bottom wall for said U, to increase the resilient action of said conductors and to facilitate the insertion of said prongs, said insulator covers providing wider spaces at the doubled portions of said conductors, the rear of the conductors and of the insulator covers, however, being closely set against the rear portion of the insulator bar, said housing also having a wider front portion and a narrower rear portion, the side walls of said rear portion snugly fitting over the respective rear portions of said insulator bar, conductors and insulator covers.

7. A continuous group electric outlet, comprising an elongated housing of sheet material, having side walls, a rear wall, and an open front wall, an insulator bar on the rear wall of said housing substantially extending the whole length of the housing, the front of said bar being exposed through the opening in the front wall, two elongated sheet electric conductors resiliently yieldingly placed against the two sides of the insulator bar, an elongated plate-like insulator cover placed over each of said conductors, having a front wall, space being left between the front walls of the housing and the insulator covers, and the respective sides of the insulator bar, whereby prongs of an electric plug may be inserted between the respective sides of the bar and the conductors thereon, the front portion of said conductors being folded doubled in a generally U shaped cross section, with a rounded front or bottom wall for said U, to increase the resilient action of said conductors and to facilitate the insertion of said prongs, said insulator covers providing wider spaces at the doubled portions of said conductors, the rear of the conductors and of the insulator covers, however, being closely set against the rear portion of the insulator bar, said housing also having a wider front portion and a narrower rear portion, the side walls of said rear portion snugly fitting over the respective rear portions of said insulator bar, conductors and insulator covers, depressions being provided in the rear of said insulator bar, the rear ends of said conductors and said insulator covers being hooked into said depressions.

8. A continuous group electric outlet, comprising an elongated housing of sheet material, having side walls, a rear wall, and an open front wall, an insulator bar on the rear wall of said housing substantially extending the whole length of the housing, the front of said bar being exposed through the opening in the front wall, two

elongated sheet electric conductors resiliently yieldingly placed against the two sides of the insulator bar, an elongated plate-like insulator cover placed over each of said conductors, having a front wall, space being left between the front walls of the housing and the insulator covers, and the respective sides of the insulator bar, whereby prongs of an electric plug may be inserted between the respective sides of the bar and the conductors thereon, the front walls of said insulator covers being closely set against said insulator bar, the edges of the opening in the front wall of said housing being set at a pre-determined distance from said insulator bar, and apertures being provided in the front of said insulator covers to permit the insertion of said prongs of an electric connector plug, the material of the insulator cover separated to form said apertures being bent over the adjacent marginal portions of the front wall of said housing to prevent an electrical contact between said prongs and said housing.

9. A portable conductor group electric outlet, comprising an elongated housing of sheet material, having side walls, a rear wall, and an open front wall, an insulator bar on the rear wall of said housing substantially extending the whole length of the housing, the front of said bar being exposed through the opening in the front wall, two elongated sheet electric conductors resiliently yieldingly placed against the two sides of the insulator bar, an elongated plate-like insulator cover placed over each of said conductors having a front wall, space being left between the front walls of the housing and the insulator covers, and the respective sides of the insulator bar, whereby prongs of an electric plug may be inserted between the respective sides of the bar and the conductors thereon, the front portion of said conductors being folded doubled in a generally U shaped cross section with a rounded front or bottom wall for said U, to increase the resilient action of said conductors and to facilitate the insertion of said prongs, said insulator covers providing wider spaces at the doubled portions of said conductors, the rear of the conductors and of the insulator covers, however, being closely set against the rear portion of the insulator bar, said housing also having a wider front portion and a narrower rear portion, the side walls of said rear portion snugly fitting over the respective rear portions of said insulator bar, conductors and insulator covers, two end walls for said housing insulated from said conductors, and means to electrically connect said conductors through one of said end walls with the respective poles of a source of current.

10. In a portable group electric outlet, as set forth in claim 9, the front walls of said insulator covers being closely set against said insulator bar, the edges of the opening in the front wall of said housing being set at a pre-determined distance from said insulator bar, and apertures being provided in the front of said insulator covers to permit the insertion of said prongs of an electric connector plug, the material of the insulator cover separated to form said apertures being bent over the adjacent marginal portions of the front wall of said housing to prevent an electrical contact between said prongs and said housing.
